UNITED STATES PATENT OFFICE.

HERBERT W. CHENEY, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

SWITCH FOR ELECTRIC CIRCUITS.

981,063.

Specification of Letters Patent. Patented Jan. 10, 1911.

Application filed November 29, 1907. Serial No. 404,349.

To all whom it may concern:

Be it known that I, HERBERT W. CHENEY, citizen of the United States, residing at Norwood, in the county of Hamilton and State 5 of Ohio, have invented certain new and useful Improvements in Switches for Electric Circuits, of which the following is a full, clear, and exact specification.

My invention relates to electric switches, 10 especially to those which open automatically on overload.

In most of the automatic overload circuit-breakers now in general use the movable contacts have a reciprocating movement. 15 This is the case whether they move rectilinearly or curvilinearly. As the result of this kind of movement the circuit is made and broken at the same points in the switch, so that the pitting of the contacts caused 20 by the arcing which takes place on interrupting the circuit interferes with the proper making of the circuit on closing the switch.

In brief, my improved circuit-breaker consists of contacts arranged to be engaged and 25 disengaged by relative movement in the same direction, and a reciprocable arm arranged when moved in one direction to bring said contacts into engagement and when moved in the other direction to disengage said contacts. Preferably one of said contacts is 30 fixed and the other is mounted on the periphery of a rotatable drum which also carries other similar contacts, the various contacts carried by the drum being arranged to co- 35 operate successively with the fixed contact. There is also preferably provided within such drum a coiled conductor which is in circuit when the switch is closed and acts as a blow-out magnet as the switch is opened. 40 This same coiled conductor may also be arranged to act as an overload magnet and release a catch which normally prevents movement of said drum to separate one of the contacts carried thereby from the fixed 45 contact, in such case the reciprocable arm being biased in the proper direction to cause such movement of the drum.

The various novel features of my invention will appear from the description and 50 drawings and will be particularly pointed out in the claims.

Figures 1 and 2 are side elevations of my improved circuit-breaker, showing it in

closed and open position respectively; Fig. 3 is a front elevation of the circuit-breaker 55 of Fig. 1, showing some of the parts in section; Fig. 4 is a bottom view of the switch as shown in Fig. 1, the operating handle being in section; Fig. 5 is a view showing the operating mechanism alone, the parts 60 being in closed position; and Fig. 6 shows somewhat diagrammatically the electrical connections.

The frame 10 of non-magnetic material has a base portion provided with the proper 65 bolt holes for fastening it to the base 11, and two side arms or bracket portions for supporting the switch parts. In the outer end of the two bracket portions is fixed a shaft 12 of magnetic material. Loosely 70 mounted on the shaft 12 is the sleeve 13 which carries the drum 14, the latter being made up of two outer disks 15 of metal or other conducting material, within which, though separated therefrom by insulation 75 16, is a coil of strap conductor 17. The inner end of the coil 17 is connected to the metal disks 15, while the outer end thereof is connected to the contacts 18^a, 18^b and 18^c, here shown as three in number and as being 80 equally spaced around the periphery of the drum 14. As the drum is rotated in one direction, say clockwise as seen in Fig. 1, the contacts 18^a, 18^b and 18^c are arranged to be brought successively into engagement with 85 the stationary spring-mounted contact 19, located in a blow-out chute 20. This blow-out chute is supported between the in-turned ends of two arms 21, which are of magnetic 90 material and are fixed on the shaft 12 so that their ends form poles of the electromagnet formed by the coil 17 and shaft 12. Thus a magnetic field is supplied for extinguishing any arc between the contacts of the 95 circuit breaker. The disks 15, to which the inner end of the coil 17 is connected, are in constant engagement with brushes 22, which thus serve to take off the current from the inner end of said coil. The brushes 22 and contact 19 are the electrical terminals of this 100 switch.

A notched disk 25 is fixed to the sleeve 13 so that it rotates with the drum 14. Arms 26 and 27 are loosely mounted on the shaft 12 and carry at their outer end pawls 28 and 29 respectively, which are spring-pressed 105

inwardly into engagement with the periphery of the disk 25. The latter is provided with three notches, one side of each of the notches being higher than the other, as best 5 shown in Fig. 5. The arm 26 is integral with one side of the U-shaped handle member 30. Links 31 and 32 are connected at one end to the arm 27 and the handle member 30 respectively, the other ends of said links being pivoted together and to the free end of the arm 33, which is pivoted to the frame 10.

The switch is shown in open position in Fig. 2. To close the switch handle 30^a is moved in a clockwise direction to the position shown in Fig. 1, the pawl 28 by its engagement with one of the notches of disk 25 carrying the drum 14 through the same angle as the handle 30^a is moved. The switch is closed when the parts reach the position shown in Fig. 1, the circuit being complete from the stationary contact 19 to the contact 18^a, through the coil 17 and disks 15 to the brushes 22. The engagement of the stops 38 and 38^a prevents further clockwise 20 movement of the handle. As the parts reach the positions shown in Fig. 1, the cam surface 34^a on a fixed arm 34 lifts the pawl 28 so that it will clear the lower or counter-clockwise side of the notch in the disk 25 25 with which it has been in engagement at substantially the same time the pawl 29 drops into one of the other notches in the disk 25, as shown in Fig. 1. The roller 35 on the inner end of the spring-pressed arm 36 is also moved inwardly at this time to engage the end of pawl 29 to prevent its clockwise movement from this position. If the handle 30^a were released with the switch not fully in the position shown in Fig. 1, the 30 spring 37, by which the handle member 30 is biased in a counter-clockwise direction, would have moved said member, together with the pawl 28, disk 25, and drum 14, back to the position shown in Fig. 2.

With the switch closed as shown in Fig. 1, the handle member 30 is biased in a counter-clockwise direction, but is prevented from moving in such direction by the engagement of the roller 35 with the end of the pawl 29. 45 In case it is desired to open the switch, the release button 41 is pushed upward to move the arms 36^a and 36 to disengage such roller and pawl, whereupon the spring 37, through the handle member 30, links 31, 32, and 33, 50 arm 27, pawl 29, and disk 25, moves the drum 14 farther in a clockwise direction into a position corresponding to that shown in Fig. 2, but with the contacts 18^a, 18^b and 18^c in the places where the contacts 18^c, 18^a and 18^b 55 are respectively shown. When the parts reach such position, further counter-clockwise movement of the handle member 30 is prevented by stop 38. The arms 21 are provided with rearward projections 39, which 60 serve as auxiliary poles for the magnet ex-

cited by the coil 17 and upon too great a current in such coil, the switch being closed as in Fig. 1, act upon the cross-bar 40 of the adjustable arm 36^a to move such arm to strike the upper end of the arm 36 and disengage the roller 35 and pawl 29. Upon such disengagement the handle member 30 is moved in a counter-clockwise direction and the drum 14 in a clockwise direction in the same manner as when the release button 70 41 is pushed upward. In either case, when the switch has reached the off position the pawl 28 drops into the next notch of the disk 25, and the switch can again be closed by moving the handle 30^a in a clockwise direction. In the successive operations of the switch the contacts on the drum 14 are successively brought into engagement with the stationary contact 19.

With the arrangement here shown and described all the arcing takes place between the counter-clockwise ends of the movable contacts and the clockwise end of the stationary contact, which ends may be provided with arcing tips, and the surfaces of 90 such contacts which first engage and which are in engagement in the normal closed position of the switch are not injured by such arcing.

Many modifications in the precise arrangement here shown and described may be made without departing from the spirit and scope of my invention, and all such I aim to cover in the following claims.

What I claim as new is:—

1. In a switch or circuit-breaker, a fixed contact, a rotatable member carrying a plurality of contacts for respectively co-operating with said fixed contact, a reciprocable arm, and means whereby successive movements of said arm in opposite directions respectively produce complementary movements of said rotatable member in the same direction to cause the disengagement of said fixed contact and one of the movable contacts and the engagement of said fixed contact and the next movable contact. 100

2. In a switch or circuit-breaker, a contact, a group of contacts with the individual contacts of which said first contact successively co-operates, a reciprocable arm, and means whereby successive movements of said arm in opposite directions respectively produce complementary relative movements between said contact and said group of contacts to bring the former from engagement with one to another of the latter. 115

3. In a switch for electric circuits, a fixed contact, a rotatable member carrying a movable contact, a reciprocable arm, and mechanical connections between said arm and said member by which upon a movement of said arm in one direction the rotatable member is rotated forward to bring the two contacts into engagement, and upon a move- 125 130

ment of said arm in the other direction the rotatable member is rotated forward to separate said two contacts.

4. In a switch for electric circuits, a fixed contact, a rotatable member carrying a movable contact, a reciprocable arm biased in one direction, and mechanical connections between said arm and said member by which upon a movement of said arm in one direction the rotatable member is rotated forward to bring the two contacts into engagement, and upon a movement of said arm in the other direction the rotatable member is rotated forward to separate said two contacts.

5. In a switch for electric circuits, a fixed contact, a rotatable member carrying a movable contact, a reciprocable arm biased in one direction, mechanical connections between said arm and said member by which upon a movement of said arm in one direction the rotatable member is rotated forward to bring the two contacts into engagement, and upon a movement of said arm in the other direction the rotatable member is rotated forward to separate said two contacts, and means for normally preventing movement of said arm in said latter direction when it is at its limit of movement in the former direction.

6. In a switch for electric circuits, a fixed contact, a rotatable member carrying a movable contact, a reciprocable arm biased in one direction, mechanical connections between said arm and said member by which upon a movement of said arm in one direction the rotatable member is rotated forward to bring the two contacts into engagement, and upon a movement of said arm in the other direction the rotatable member is rotated forward to separate said two contacts, means for normally preventing movement of said arm in said latter direction when it is at its limit of movement in the former direction, and means for releasing said arm from said preventive means.

7. In a switch for electric circuits, a fixed contact, a rotatable member carrying a movable contact, a reciprocable arm biased in one direction, and mechanical connections between said arm and said member whereby upon a movement of said arm against its bias the rotatable member is moved to bring the two contacts in engagement, and upon a movement in the direction of its bias the rotatable member is moved in the same direction as before to separate said contacts.

8. In a switch for electric circuits, a fixed contact, a rotatable member carrying a movable contact, a reciprocable arm biased in one direction, mechanical connections between said arm and said member whereby upon a movement of said arm against its bias the rotatable member is moved to bring the two contacts in engagement, and upon a

movement in the direction of its bias the rotatable member is moved in the same direction as before to separate said contacts, and means for normally preventing movement of said arm in one direction when it is at its limit of movement in the other direction.

9. In a switch for electric circuits, a fixed contact, a rotatable member carrying a movable contact, a reciprocable arm biased in one direction, mechanical connections between said arm and said member whereby upon a movement of said arm against its bias the rotatable member is moved to bring the two contacts in engagement, and upon a movement in the direction of its bias the rotatable member is moved in the same direction as before to separate said contacts, means for normally preventing movement of said arm in one direction when it is at its limit of movement in the other direction, and means for releasing said arm from said preventive means.

10. In a switch for electric circuits, a contact, a group of contacts with the individual contacts of which said first contact successively coöperates, a reciprocable arm, and means whereby the alternate half reciprocations of said arm bring said first contact successively into engagement with the contacts of said group, and the remaining half reciprocations successively separate the engaging contacts.

11. In a switch for electric circuits, a contact, a group of contacts with the individual contacts of which said first contact successively coöperates, a reciprocable arm, and means whereby the alternate half reciprocations of said arm bring said first contact successively into engagement with the contacts of said group, and the remaining half reciprocations successively separate the engaging contacts, said arm being biased in the direction to separate said contacts.

12. In a switch for electric circuits, a contact, a group of contacts with the individual contacts of which said first contact successively coöperates, a reciprocable arm, means whereby the alternate half reciprocations of said arm bring said first contact successively into engagement with the contacts of said group, and the remaining half reciprocations successively separate the engaging contacts, said arm being biased in the direction to separate said contacts, and means for normally preventing movement of said arm to separate said contacts.

13. In a switch for electric circuits, a contact, a group of contacts with the individual contacts of which said first contact successively coöperates, a reciprocable arm, means whereby alternate half reciprocations of said arm respectively bring said first contact into engagement with one of the contacts of said group and separate the engaging contacts by relative movements between the contacts.

in the same direction, said arm being biased in the direction to separate said contacts, means for normally preventing movement of said arm to separate said contacts, and 5 means for releasing said arm from said preventive means.

14. In a switch for electric circuits, a contact, a group of contacts with the individual contacts of which said first contact successively coöperates, a reciprocable arm, means whereby alternate half reciprocations of said arm respectively bring said first contact into engagement with one of the contacts of said group and separate the engaging contacts, 10 said arm being biased in the direction to separate said contacts, means for normally preventing movement of said arm to separate said contacts, and means for releasing said arm from said preventive means upon an 15 overload.

15. In a switch for electric circuits, a contact, a group of contacts with the individual contacts of which said first contact successively coöperates, a reciprocable arm, means 20 whereby alternate half reciprocations of said arm bring said first contact successively into engagement with the contacts of said group, and the remaining half reciprocations successively separate the engaging contacts, 25 said arm being biased in the direction to separate said contacts, means for normally preventing movement of said arm to separate said contacts, and means for releasing said arm from said preventive means either 30 manually or upon the occurrence of abnormal conditions.

16. In a switch or circuit-breaker, the combination of a fixed contact, a rotatable member carrying a movable contact arranged to 40 coöperate with said fixed contact, means for rotating said rotatable member in the same direction to engage and disengage said contacts, and a spiral coil of ribbon conductor within said rotatable member for furnishing 45 a magnetic field at the contacts as they are disengaged.

17. In a switch or circuit-breaker, the combination of a fixed contact, a rotatable member carrying a plurality of movable contacts arranged to be successively brought 50 into engagement with said fixed contact as the rotatable member is rotated, a coiled conductor within said rotatable member, said conductor being connected at one end to the

contacts carried by said member and ar- 55 ranged to furnish a magnetic field at the fixed contact.

18. In a switch or circuit-breaker, the combination of a fixed contact, a rotatable member carrying a plurality of contacts arranged 60 to be successively brought into engagement with said fixed contact as the rotatable member is rotated, a shaft of magnetic material for said rotatable member, projections of 65 magnetic material from said shaft which extend into proximity to said fixed contact, and a coiled conductor within said rotatable member and having its outer end connected to the contacts carried by the rotatable member.

19. In a switch or circuit-breaker, the combination of a fixed contact, a rotatable member carrying a plurality of contacts arranged 70 to be successively brought into engagement with said fixed contact as the rotatable member is rotated, means for biasing said member to disengage said fixed contact and any one of the movable contacts with which it is in engagement, means for normally preventing movement of said rotatable member 75 when such contacts are in engagement, and a coiled conductor within said member arranged to release the latter from said preventive means upon an overload.

20. In a switch or circuit-breaker, the combination of a fixed contact, a rotatable member carrying a plurality of contacts arranged 80 to be successively brought into engagement with said fixed contact as the rotatable member is rotated, means for biasing said member to disengage said fixed contact and any one of the movable contacts when they are 85 in engagement, means for normally preventing movement of said rotatable member when such contacts are in engagement, and a coiled conductor within said member arranged to release the latter from said preventive means upon overload and to furnish 90 a magnetic field at said fixed contact as it is disengaged from one of said movable contacts.

In testimony whereof I affix my signature, in the presence of two witnesses.

HERBERT W. CHENEY.
